(57) **CLAIM**

The ornamental design for a folding hood for a personal therapy compartment, as shown and described.

DESCRIPTION

FIG. 1 is a front perspective view of a folding hood for a personal therapy compartment embodying our new design; FIG. 2 is a left side view thereof, the other side being a mirror image thereof;

FIG. 3 is a top plan view thereof;

FIG. 4 is a front view thereof;

FIG. 5 is a rear view thereof; and,

FIG. 6 is a bottom plan view thereof.

The broken line showing is for illustrative purposes only and forms no part of the claimed design.
